SHEET PAPER DISPENSER

Wyatt H. Ensminger, St. Helena, Calif.

Application April 22, 1941, Serial No. 389,725

5 Claims (Cl. 242—55.5)

The invention relates to a device for dispensing desired lengths of sheet paper from a roll, and in its present embodiment is designed for dispensing lengths of waxed sheet paper from a roll such as marketed for household use.

An object of the invention is to provide a dispenser of the character described which will keep the paper fully protected from exposure before being withdrawn from the device, and will permit the user to sever the sheet in a ready manner and grip and withdraw the sheet from the device, notwithstanding the fact that the leading edge of the sheet may be inaccessible after severance of the preceding portion.

Another object of the invention is to provide a dispenser having all of the parts mounted on two distinct units which are arranged to be separated from each other to permit refilling the dispenser and which are so designed and have the parts arranged thereon in such manner that the reassembly of the units on the refilling operation will serve to automatically position and thread the paper through the cooperating parts.

A further object of the invention is to provide a dispenser of the character described which will be attractive in appearance, inexpensive to manufacture, easy to operate, and not apt to become out of order when subjected to careless usage.

The invention possesses other objects and features of advantage, some of which with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a perspective view of a dispenser designed in accordance with my invention.

Figure 2 is a transverse sectional view of the dispenser taken on the line 2—2 of Figure 1.

Figure 3 is a fragmentary longitudinal sectional view taken on the line 3—3 of Figure 1.

Figure 4 is a longitudinal sectional view of the dispenser on a reduced scale.

Figure 5 is a transverse sectional view similar to Figure 2 but showing a modified construction.

Figure 6 is a fragmentary sectional view taken on the line 6—6 of Figure 5.

As illustrated in the drawing, the dispenser of my invention is made up of two distinct units 12 and 13 respectively comprising a receptacle and cover. The receptacle is formed open at the top

to permit insertion of a roll of waxed paper or the like such as available on the market, and is provided with a bottom wall 14, end walls 15 and front and rear walls 17 and 18 which are of such size as to support and accommodate the roll therebetween. The cover is provided with an open bottom so that the receptacle may be inserted within the cover, and is formed with a top wall 19, front and rear walls 21 and 22 and end walls 23 corresponding in general to the similar walls of the receptacle, the end walls of the cover being, however, appreciably wider than the end walls of the receptacle so that a space 24 may be left between the front walls 17 and 21 when the units are in assembled relation.

In the present embodiment of the invention the dispenser is arranged for support on a wall or the like and the attachment of the device in position is arranged to be effected through means of the cover. For this reason there is provided in the rear wall 22 suitable slots 26 through which may be inserted suitable screws 27 for fastening the cover to the wall. To releasably hold the receptacle in the cover with the space 24 defined as aforesaid, there is provided on each of the end walls of the cover a pivoted spring pressed hook 28 which is designed to engage a pin 29 projecting from the end walls of the receptacle, a slot 31 being provided in the end walls of the cover so as to accommodate and guide the pin.

As will be clear from Figure 2, the front wall 17 of the receptacle is foreshortened at the top so as to provide an outlet opening for the sheet from the receptacle and preferably the upper edge 32 of such wall is rolled so as to provide a smooth guide for the sheet over such wall. The sheet, as will also be clear from said figure, is arranged to be drawn from over the upper edge 32 down through the space 24 and through a discharge opening 33 defined between the lower edge of the wall 17 and the wall 21. The lower edge 34 of wall 21 is preferably serrated or otherwise formed to permit the ready severance of the sheet when the portion extending from the opening 33 is pulled against and across such edge. As will be evident, when the sheet is severed at the edge 34 the leading portion of the sheet remaining attached to the roll is left hidden and relatively inaccessible in the space 24. In order, therefore, to advance the sheet through the opening 33 so as to permit gripping by the user for withdrawal and severance of another length of the sheet, I provide cooperating means on the receptacle and cover, which may be actuated from the exterior of the cover to initially advance

the sheet when it is desired to withdraw and remove a length after the previous severing operation. In accordance with the above I provide a pair of friction rollers 36 and 37 respectively carried by the receptacle and cover. The rollers which are preferably formed of rubber and arranged in parallel relation, are designed to project into the space 24 so as to resiliently grip between them the portion of the sheet extending through the space. One of the rollers has a fixed mounting, while the other is mounted to permit it to be yieldingly urged toward the other. As here shown, the roller 36 is mounted for rotation about a fixed axis and accordingly is provided with a shaft 38 mounted in fixed bearings 39 attached to the front wall of the receptacle. As will be clear from Figure 3, such wall is provided with a slot 41 and the roller is positioned so as to extend through the slot and into the space 24. The front wall 21 is slotted at 42 similar to the wall 17 so as to accommodate the roller 37, part of which is arranged to extend into the space 24 and outside the wall 21 so as to be accessible to the user for gripping and rotation. Roller 37 is provided with a shaft 43 which is mounted in bearings 44 which permit movement of the shaft transversely of the axis or in other words, to and from the roller 36. In order to urge the roller 37 toward the roller 36 and thereby insure the gripping of the sheet between the rollers, a spring 46 is inserted in the bearings to engage and press the shaft 43 toward the bearings 44 for the roller 36. A modified form of mounting for the roller 37 is shown in Figures 5 and 6. In this embodiment the roller shaft 43 is provided on an arm 47 pivotally connected to the front wall 21 above the slot 42, the arm being forced by a spring 48 to urge the roller 37 rearwardly towards the roller 36. The arm 47 as well as the bearings 44 may be positioned inwardly or outwardly of the wall 21. However, it is preferable to position the same on the inner side of the wall, as here illustrated, so as to conceal such parts. Preferably the wall 21 is bowed outwardly so as to permit the mounting for the roller 37 to be more conveniently carried and arranged on the inner side of the wall. It will now be clear that with the sheet positioned between the rollers the operator may readily advance the same so that the leading edge will extend through the passage 33 by simply moving in the proper direction the portion of the roller 37 protruding outwardly from the wall 21.

It is important to note that the design and arrangement of the rollers 36 and 37 are such that the receptacle may be disengaged from the cover and replaced in position without requiring manipulation of the roller mountings or related parts. In other words, not only may the units be readily separated for refilling the receptacle without requiring manipulation of the rollers and associated parts, but the units may be correspondingly re-assembled to automatically position and thread the sheet in and through the rollers for withdrawal in the required manner. Thus, to permit the separation of the units, it is merely necessary to release the hooks 28, so that the receptacle may be lowered through the opening in the bottom of the cover. When a new roll is then inserted in the receptacle with a portion folded over the guide 32 and with sufficient length depending from the lower edge of the wall 17, the receptacle is reinserted into the cover so that the sheet is positioned in the space 24 and gripped between the two rollers. It will thus be seen

that it is practically impossible to reinsert the receptacle without positioning the sheet and parts in proper operative relation.

I claim:

- 5 1. In a sheet paper dispenser of the character described, a receptacle having a slotted front wall and formed for supporting a roll of sheet paper therein with a free end portion extending downwardly over the outer-side of said wall, a roller carried by said receptacle and extending through said slot for engagement with said sheet portion, a cover for said receptacle provided with a front wall positioned opposite said receptacle wall and having a lower serrated edge and a slot in registration with said roller, and a roller carried by said cover wall positioned with a portion protruding from the outer-side and a portion protruding from the inner side to press said sheet portion against the first roller.
- 10 2. In a sheet paper dispenser of the character described, an open top receptacle designed to support a roll of sheet paper and having a front wall over and down across the outer side of which the sheet is arranged to be drawn, a cover for said receptacle mounted to overlie said receptacle front wall in spaced relation and having a front wall parallel to and spaced from said receptacle front wall whereby the sheet may be extended downwardly therebetween and having a paper severing edge at the bottom thereof, a roller carried by said receptacle front wall in position to engage the sheet, and a roller carried by said cover front wall positioned to engage said sheet opposite said first roller and having a portion of its periphery exposed at the outer side of said cover front wall for manual engagement and rotation.
- 15 3. In a sheet paper dispenser of the character described, a receptacle having a bottom and front and rear walls for supporting and positioning a roll of paper therein, a cover for enclosing said receptacle having a top and front and rear walls positioned opposite the corresponding walls of the receptacle and with the front walls spaced apart for the passage of the sheet therebetween, the front wall of the receptacle being foreshortened at the top and formed to provide a guide for the sheet from the roll to the space between the front walls, means to releasably hold the receptacle and cover in assembled relation, a roller carried on said receptacle front wall protruding into said space, said cover front wall having a lower cutting edge and a slot opposite said roller, and a roller carried by said cover and positioned in said slot with a portion extending outwardly from the wall and a portion projecting into said space for cooperation with said first roller in gripping the sheet therein.
- 20 4. In a sheet paper dispenser of the character described, a receptacle designed to contain a roll of paper and having a front wall providing a guide over which the sheet from the roll is drawn, a cover enclosing the receptacle having a front wall provided with a slot and positioned opposite to and separated from said receptacle front wall to provide a vertical extending space therebetween for the sheet from the roll, said cover front wall being bowed outwardly from said container front wall to increase the width of said space, a roller carried by said cover in said slot and projecting into said space and outwardly from the front wall of the cover, and a roller carried by the front wall of the receptacle opposite said first roller and extending into said space for

cooperation with said other roller to grip the sheet therein.

5. In a sheet paper dispenser an open bottomed cover arranged for attachment to a wall or the like and including top and side front walls, an open-topped sheet paper roll receptacle formed to fit within said cover walls and having a bottom and walls substantially corresponding with and positionable opposite to the walls of the cover with a space between the front walls of said cover and receptacle to provide for the passage of the paper from the roll and the outlet of the paper

from said space, cooperating fastening means on the receptacle and cover for releasably holding the receptacle in the cover and permitting downward removal of the receptacle from the cover, and cooperating rollers carried by the receptacle and cover at said front walls and extending into said space for engagement with the sheet, the roller on the cover having a portion of the periphery thereof exposed and accessible for turning at the outer side of the cover.

WYATT H. ENSMINGER.
